UNITED STATES PATENT OFFICE.

DANTE E. DONATI, OF CAYUCOS, CALIFORNIA.

SHELL-EXTRACTOR.

No. 892,230.

Specification of Letters Patent.

Patented June 30, 1908.

Application filed January 8, 1907. Serial No. 351,387.

To all whom it may concern:

Be it known that I, DANTE E. DONATI, a citizen of the United States, residing at Cayucos, in the county of San Luis Obispo, 5 State of California, have invented certain new and useful Improvements in Shell-Extractors; and I do hereby declare the following to be a full, clear, and exact description of the invention, such as will enable 10 others skilled in the art to which it appertains to make and use the same.

This invention relates to shell extractors and more particularly to that class which are designed for actuation by the shell ejecting 15 mechanism of the gun or rifle and the device is designed for use in extracting shells that have had their heads blown off or have become split due to repeated re-loading and re-firing.

20 While numerous tools have been designed for this purpose, they have proven generally unsatisfactory for the reason that they are unnecessarily complicated. The device embodied in my invention comprises but two 25 members, a mandrel member and an expandable sleeve member, which is permanently engaged upon the mandrel member.

In the accompanying drawings, Figure 1 30 is a side elevation of an extractor constructed in accordance with my invention. Fig. 2 is a similar view showing the extractor after having been driven to its initial position in the shell. Fig. 3 is a view similar to Fig. 2 but illustrating the position of the mandrel and 35 sleeve member of the extractor when the same is being withdrawn from the gun or rifle.

Referring more specifically to the drawings, 40 the extractor is shown as comprising a mandrel member 5 and a sleeve member 6. The mandrel member is in the form of a stem which is provided at one of its ends with a head 7 of substantially the same diameter as the head of the shell used in the gun or rifle 45 and this head may either be formed integral with the stem or, as shown in the drawings, it may have a screw threaded connection

therewith, this latter form being preferable for the reason that when so constructed, the sleeve 6 may be removed when desired. At 50 its end opposite its head end the stem comprising the mandrel is flared as at 8, to such a degree that it will have substantially the same diameter as the muzzle of the shell. The sleeve 6 is of slightly less length than the 55 stem comprising the mandrel and normally has a slight play upon the stem. The sleeve however is slit in opposite sides as at 9, at that end adjacent the flared end of the stem, it being understood of course that by thus 60 slitting the sleeve, it may be expanded by the flared portion of the stem.

In using my extractor, the same is introduced into the decapitated shell and forced thereinto, the sleeve being of such diameter, 65 before being expanded, that it will fit snugly within the muzzle of the shell. The extractor lever of the gun or rifle is then worked as in extracting the automatic shell and it will be understood that the mandrel, being withdrawn, will expand the sleeve and cause the 70 same to grip the shell with sufficient frictional force to permit of its extraction by an ejecting mechanism of the gun.

What is claimed is:

75 A shell extractor comprising a mandrel formed at one end with a head and flared at the other end, and a sleeve fitted snugly upon the shank of the mandrel, the sleeve being of but slightly less length than the distance between the head of the mandrel and the minor end of its lower portion and being formed in opposite sides with slits which are of slightly greater length than the flared portion, the said flared portion being designed to expand 80 the slit portion of the sleeve within the muzzle of a shell.

85 In testimony whereof, I affix my signature, in presence of two witnesses.

DANTE E. DONATI.
